UNITED STATES PATENT OFFICE.

FREDERICK L. VERNON, OF NEWTON, IOWA.

DESIGN FOR A MATCH-HOLDER.

44,326.

Specification for Design.

Patented July 8, 1913.

Application filed March 28, 1913. Serial No. 757,447. Term of patent 3½ years.

To all whom it may concern:

Be it known that I, FREDERICK L. VERNON, a citizen of the United States of America, and resident of Newton, Jasper county, Iowa, have invented a new, original, and ornamental Design for a Match-Holder, of which the following is a specification.

The object of this invention is to provide an ornamental design for a match holder.

My invention consists of the ornamental design, hereinafter set forth, pointed out in my claim and illustrated by the accompanying drawing, in which the view is a perspective illustrating the complete design.

I claim as my invention—

The ornamental design for a match holder, as shown.

Signed by me at Newton, Iowa, this twenty fourth day of February, 1913.

FREDERICK L. VERNON.
